MEDICAL INSTRUMENT

Arnold Landau, Berlin-Friedenau, Germany, assignor to the firm, Elektricitatsgesellschaft "Sanitas" m. b. H., Berlin, Germany

Application November 2, 1929, Serial No. 404,332
In Germany October 8, 1927

9 Claims. (Cl. 174—89)

My invention relates to medical instruments and more particularly to instruments designed for the application of high frequency currents.

It is an object of my invention to provide means whereby sparking at the body of the patient is eliminated. To this end I so design my instrument that the circuit for the electric current is completed only after contact has been established between the instrument and the body

10 of the patient.

It is another object of my invention to avoid electric reactions on the body of the operator. To this end I provide a separate circuit in connection with a relay, and I connect the circuit 15 of the relay with the handle of the instrument so that in case of any leakage only the comparatively weak current of the relay circuit and not the strong current of the line circuit, will flow through the body of the operator.

20 In the drawing affixed to this specification and forming part thereof various instruments embodying my invention are illustrated diagrammatically by way of example.

In the drawing

25 Fig. 1 is a partly sectional plan view of an instrument of the tonsillotome or adenotome type, without a relay.

Fig. 2 is a diagram of connections showing a relay with a battery circuit,

30 Fig. 3 is a diagram showing a relay the circuit of which is shunted from the line wires,

Fig. 4 is a diagram showing a mechanically operated relay,

35 Fig. 5 is a diagram showing an instrument having a relay in a battery circuit as in Fig. 2, but with a modified arrangement of the blade, and

40 Fig. 6 is a diagram showing an instrument in which the circuit of the relay is completed through the body of the patient.

Referring now to the drawing and first to Fig. 1, 1 is a casing of insulating material which at its front end is provided with a loop or guide 2. The guide is grooved for the reception of the 45 blade 3, which is one of the electrodes. 4 is a handle with an eye 7 which handle is fitted to slide in the casing 1, 5 is the opposite electrode which is seated on the threaded end 8 of the handle 4, 13 is an insulated or insulating bush 50 on the electrode which serves as an abutment for a spring 6, 14 is the mating bush at the other end of the spring 6, 9 is a slide secured to the inner end of the blade or electrode 3, 10 is a conductor in the slide 9, 15 is a conductor which 55 is connected with a contact spring 12, the contact

spring sliding on the electrode 5 with its end 16, 17 is a contact spring at the end of the electrode 5 which together with a reduced projection 18 at the end of the electrode, makes a sort of clamp or seat for the pointed end of the conductor 10, and 11 is a shoulder at the inner end of the slide 7 which, when the circuit is closed at 10, 17, 18, is engaged by the end of the spring 16, breaks the circuit and holds the slide in position. Another conductor, not shown, is provided for carrying away the current from the electrode 3. The handle 4 is of insulating material as shown but obviously might be of conducting material, and insulated from the electrode 5.

In operation, the instrument is placed on a part of the patient's body, for instance a tonsil, and then pressure is applied on the handle 7 to push the electrode 5 toward the point of the conductor 10.

It will be understood that the blade 3 is advanced freely until it contacts with the tonsil and thereupon an increasing pressure reaction is exerted on the spring 6 but still the circuit is not closed so that the electrode 3 is applied without sparking.

Only after the spring 6 has been compressed to such an extent that the circuit is closed at 17 and 18, current flows in the electrode, while the blade 3 still advances for separating the tonsil.

When the blade has been advanced so far that the end 16 of spring 12 engages behind the shoulder 11 of the slide 4 the circuit is broken and remains in this condition until the slide is released by turning it through about 90 degrees. In this manner, sparking at the body of the patient when removing the instrument is also eliminated as the slide 4 will only be released after the instrument has been retracted from the body of the patient.

In the operation of the instrument as described, it is seen that the spring 6 and the electric switch, comprising the contact elements 17, 18 and the pointed end of the conductor 10, act as means for temporarily preventing flow of diathermic current when the tool or blade 3 is in its initial position prior to an operative stroke and for permitting flow of said current through a patient's body during such operative stroke; said means being operated by and substantially simultaneously with contact of said tool with said patient's body. The spring 12 cooperating with shoulder 11 acts as means for breaking the diathermic current at the conclusion of an operative stroke without independent manipulation; that is breaking of the current occurs as an incident of the operating stroke.

In this, the simplest form of the instrument, 5
sparking at the blade 3 is avoided at the beginning
and at the end of the operation but still there is
the risk of injury to the operator through leakage
from the electrode 5. This is avoided in the sev-
eral arrangements the diagrams of which are il-
lustrated in Figs. 2-6.

Referring first to Fig. 2, the electrodes 3 and 5,
with the spring 6 between them, are indicated
10 only diagrammatically. The body of the patient,
a tonsil as assumed in the present instance, is in-
dicated by the sectioned area 19, 20 are the line
wires of a system, 21 is a diathermic apparatus
15 of any suitable kind, 22 and 23 are wires extend-
ing from the apparatus to the blade 3 and the
tonsil 19, respectively, 24 is a battery, 26 is a relay
in the diathermic apparatus, and 27, 28 are the
wires of the relay-and-battery circuit.

It will be understood that when the electrodes
20 3 and 5 get into contact, as described with ref-
erence to Fig. 1, the circuit 27, 28 of the relay 26 is
closed and the relay cuts in the circuit 22, 23
through the blade 3 and the body of the patient.
Here, sparking is also avoided because the circuit
25 of the relay 26, and consequently the circuit 22,
23 can only be closed after the electrode 3 has
come into contact with the body of the patient
but, in addition, the operator is protected against
the strong current from the system 20.

Referring now to Fig. 3, the arrangement is the
30 same as described with reference to Fig. 2, with
the exception that the circuit of the relay 26 is
constituted by a shunt 29, 30 from the system 20.

Referring now to Fig. 4, the relay 26 is here
35 operated mechanically through the medium of a
flexible bar 31 which is attached to the electrode 5
and is fitted to slide in a flexible tube 32 which
is secured at one end to the electrode 3.

Referring now to Fig. 5, this illustrates an ap-
40 paratus in which the electrode 5 is not pushed but
pulled as indicated by the arrow. The spring 6 is
inserted between an extension 25 of the electrode
5, and an extension 33 at the end of the blade or
electrode 3, which in the present instance is
45 designed like the loop 2, Fig. 1, with an opening 34.
The blade 3 is placed on the tonsil 19 so as to en-
gage it with the closed end of the loop 34, and a
pull is exerted at the end of the electrode 5 until
the extensions 25 and 33 make contact, closing
50 the circuit of the battery 24 and the relay 26.
Otherwise, the operation is the same as that de-
scribed with reference to Fig. 2.

Referring now to Fig. 6, the blade 3 is the single
55 electrode, the electrode 5 having been omitted,
and the blade 3 is directly engaged by a handle
or the like, not shown, so as to push it toward the
tonsil 19. The battery 24 is connected through
the wire 27 with an electrode 35 which engages
60 the tonsil 19. The wire 28 extends from the blade
3 to the relay 26 as described, a wire 36 connect-
ing the battery 24 with the relay 26. The wire 22
is connected with the blade 3, and the wire 23 is
connected with another electrode 37 which is also
65 adapted to be placed in contact with the tonsil
19. It will appear that when the blade 3 is placed
in contact at 19 the circuit of the relay 26 is
closed through 3, 28, 36, 24 and 27, whereupon
the relay makes the circuit 22, 23 which is com-
70 pleted through the body of the patient at 19.

In the systems having a battery 24 in the relay
circuit, the battery might be replaced by a trans-
former, not shown, the primary coil of which is
connected with the system so that the secondary
supplies only low-voltage current to the instru-
75 ment. The transformer should not be grounded.

In this manner an additional safety factor for the
patient and for the operator is obtained.

I wish it to be understood that I do not desire
to be limited to the exact details of construction
80 shown and described for obvious modifications
will occur to a person skilled in the art.

In the claims affixed to this specification no
selection of any particular modification of the
invention is intended to the exclusion of other
modifications thereof and the right to subse-
85 quently make claim to any modification not cov-
ered by these claims is expressly reserved.

I claim:—

1. A medical instrument fed with high fre-
90 quency current comprising a casing, a blade fitted
to slide in said casing, an electrode also fitted to
slide in said casing so as to make contact with
said blade, resilient means inserted between said
blade and said electrode so as to make up a me-
chanical connection of said blade with said elec-
trode and to advance said blade before contact is
made between it and said electrode, a contact
spring fitted to slide on said electrode, an insu-
lated handle on said electrode, a shoulder on said
95 handle adapted to be engaged and retained by
said contact spring, and a circuit connected to
said blade and said contact spring.

2. A medical instrument fed with high fre-
100 quency current comprising a casing, a blade fitted
to slide in said casing, an electrode also fitted to
slide in said casing so as to make contact with
said blade, resilient means inserted between said
blade and said electrode so as to make up a me-
chanical connection of said blade with said elec-
trode and to advance said blade before contact is
made between it and said electrode, a contact
spring fitted to slide on said electrode, an insulat-
ing handle on said electrode, a shoulder on said
105 handle adapted to be engaged and retained by
said contact spring, and a circuit connected to
said blade and said contact spring.

3. A medical instrument fed with high fre-
110 quency current comprising an operating tool, a
circuit for supplying heating current to said tool,
means for pushing said tool into contact with the
body of the patient, a resilient part inserted
between said pushing means and said tool, and
a switch in said circuit adapted to be operated
by the reaction of the patient's body and to
complete said circuit after contact has been made
115 at the body of the patient.

4. A medical instrument fed with high fre-
120 quency current comprising an operating tool, a
circuit for supplying heating current to said tool,
means for pulling said tool into contact with the
body of the patient, a resilient part inserted be-
tween said pulling means and said tool, and a
switch in said circuit adapted to be operated by
the reaction of the patient's body and to com-
plete said circuit after contact has been made at
125 the body of the patient.

5. A medical instrument fed with high fre-
130 quency current comprising a casing, a tool fitted
to slide in said casing, a tool operating element
also fitted to slide in said casing and normally
spaced from said tool; the said tool operating ele-
ment being adapted to approach and to operate
140 said tool during an operative stroke of said in-
strument; and means cooperating with at least
one of said tool and said tool operating elements
145 for commencing the flow of said diathermic cur-
rent upon approach of said tool operating element
to said tool during an operative stroke of said in-
strument; said means being operable by said op-
erative stroke.

6. The combination of claim 5 wherein said means comprises an electric switch having at least two contact elements, a source of diathermic current attached to one of said elements and means for holding said elements apart prior to said operative stroke and for permitting closure of said elements during said stroke. 80
7. The combination of claim 5 wherein said means comprises an electric switch having at least two contact elements and a resilient means for holding said elements apart prior to an operative stroke of said tool and for permitting closure of said elements during said operative stroke, whereby flow of said diathermic current is commenced. 85

8. The combination of claim 5 wherein said means comprises an electric switch in the circuit of said diathermic current and mechanical means for operating said switch, said mechanical means being operated incidental to the operative stroke of said tool. 90

9. The combination of claim 5 further combined with means for breaking said diathermic circuit at the conclusion of said operative stroke and for temporarily holding said tool at the end of its operative stroke without independent manipulation. 95
